UNITED STATES PATENT OFFICE.

GEORGE DAVIES, OF SEATTLE, WASHINGTON.

BICYCLE.

SPECIFICATION forming part of Letters Patent No. 633,814, dated September 26, 1899.

Application filed June 20, 1899. Serial No. 721,233. (No model.)

To all whom it may concern:

Be it known that I, GEORGE DAVIES, a citizen of the United States, and a resident of Seattle, county of King, State of Washington, have invented certain new and useful Improvements in Bicycles, of which the following is a specification, reference being had therein to the accompanying drawings, in which—

10 Figure 1 is a side elevation of a bicycle, showing the improvement. Fig. 2 is a detail plan view of the rear portion of the bicycle. Fig. 3 is a detail view, and Fig. 4 is a detail section taken on the line 4 4 of Fig. 3.

15 The object of this invention is to provide a simple device by means of which an easier foot movement may be secured than is possible with the crank mechanism now in use without increasing the length of the cranks 20 or materially increasing the foot movement required to rotate them.

Referring to the various parts by numerals, 1 designates the crank-arms of an ordinary crank-operated bicycle, to the outer ends of 25 each of which on pivot 2 is mounted a substantially horizontal lever 3, to the shorter forward arm of which latter is secured the usual pedal 4, the rear longer arm of this lever carrying at its extreme end a roller 5, this 30 roller being grooved and confined within a continuous guide or track 6, suitably fastened to the side of the bicycle-frame near the rear hub. The two cam tracks or guides are coincident with each other, and each cam has its 35 upper and lower portions formed on a circle struck from its center, the front and rear sides of the guide being bulged or extended, respectively, forward and rearward in a substantially V-shaped form, giving the guide or 40 raceway somewhat of an oval shape, the longer diameter running horizontally of the cam and being in substantially the same horizontal plane as the drive-shaft. One of the inclined parts of each of the angular or V-shaped portions of the cam is pivoted, as at 8, and adapted 45 to yield inward as the roller 5 passes over it, this pivoted part or gate being normally pressed outward into the path of the roller by means of a spring 8. The free end of each 50 pivoted part terminates at the apex of the angular or V-shaped portion of the guide.

As the bicycle is driven in the usual man-

ner by rotating the pedals the crank-arms describe a true circle and the roller 5 travels around the cam groove or track 6, the pedals 55 moving in the substantially oval-shaped orbit (shown in dotted lines in Fig. 3) which is eccentric to and forward of the center of the crank-shaft. As the roller 5 passes over each of the gates the gate is forced inward, and 60 just as the roller reaches the apex of the angular portion the gate automatically springs outward, so that its end forms an abutment or guide to direct the roller into the adjacent angular portion, whereby the roller will be 65 caused to travel continuously in one direction around the cam-track. The radius of the circular portion of the cam-guides being but slightly shorter than the radius of the crank 70 the lever 3 will be maintained in a substantially horizontal position, whereby the diameter of the orbit of the pedal will be but slightly longer than the diameter of the circle described by the crank-arm. It will be observed that my device overcomes the dead- 75 centers and materially contributes to steadiness and ease of the foot movement. On the upstroke of the pedal the crank and the forward part of the horizontal lever will overlap, and the leverage will thereby be reduced to 80 normal.

It will be observed that the increase in leverage is obtained just where it is desired—namely, upon the downstroke—the leverage beginning to increase just as the pedal passes 85 over the center and continuing to increase to a point horizontally in line with the drive-shaft and then gradually decreasing toward the lower limit of the stroke.

As will be observed, shorter crank-arms may 90 be employed than are now in use, and the loss of leverage that would thus ordinarily follow will be compensated for by the increased leverage obtained by my device, thereby making it possible to propel high-gearred 95 bicycles with less effort and a comparatively shorter foot movement.

The roller 5 is preferably grooved for better guidance around the track, the track being formed by the edges of the guide-frame, 100 and a portion of the outer frame or track is omitted at 9, so that the roller may be inserted in the guideway and removed therefrom.

I claim—

1. In combination, a crank-driven bicycle, a substantially horizontal lever attached to each crank, a pedal on the forward end of each lever and a roller on the rear end of each lever, a continuous guide-frame secured to the frame on each side and receiving and guiding the rollers on the respective levers, said guide-frame having its front portion extended forward and its rear portion extended rearward into angular or V-shaped projections or bulges, and a device at each angular part of the guide to automatically prevent the return of the roller as it passes over the center at front and back, whereby the rollers will move continuously around in the guide in the same direction as the cranks and pedals.
2. In combination with a crank-driven bicycle, a substantially horizontal lever pivoted to each crank and carrying a pedal at the for-

ward end and a roller at its rear end, continuous guides adapted to receive the rollers on the levers, one guide being affixed to either side of the frame, and said guides each having a forward angular extension at its center, ²⁵ a pivoted gate upon the upper side of said angular part said gate being normally pressed outward into the path of the roller, whereby the roller will be compelled to pass continuously around the guide and prevented from reversing its direction at the forward end of its stroke.

In testimony whereof I hereunto affix my signature, in the presence of two witnesses, this 22d day of May, 1899.

GEORGE DAVIES.
